UNITED STATES PATENT OFFICE

2,040,505

AUTOMATIC CHOKE

Glen R. Sisson, Pendleton, Ind.

Application January 20, 1930, Serial No. 422,014

18 Claims. (Cl. 123—179)

My invention is concerned with the automatic control of the fuel-air ratio in an explosive mixture produced by the carburetor of an internal combustion engine. In my prior Patents No. 1,544,350, No. 1,577,765, and No. 1,577,766, I have shown various arrangements by which the mixture proportions may be varied in accordance with the temperature of the engine and the temperature of the atmosphere, and in addition such prior patents disclose means for producing a temporary enrichment of the mixture when the engine is being cranked.

In a general way, the present invention is concerned with a device similar in purpose to those shown in my prior patents above referred to, and it is the object of the invention of this application to produce a device in the form of an attachment which will be self-contained and which may be brought into association with an internal combustion engine and its carburetor without the necessity for modification of any of the parts of the engine or carburetor. It is the further object of my invention to produce a device which will overcome certain disadvantages of the devices illustrated in my prior patents.

The accompanying drawing illustrates my invention: Fig. 1 is a fragmental side elevation of an internal combustion engine, such as an automobile engine, showing my device associated with the engine and carburetor; Figs. 2 and 3 are horizontal sections on the lines 2—2 and 3—3 of Fig. 4; Fig. 4 is a vertical section on the line 4—4 of Fig. 2; Fig. 5 is a diagrammatic view showing electric connections; and Fig. 6 is a fragmental horizontal section on the line 6—6 of Fig. 4.

The engine 10 shown in the drawing has the usual inlet manifold 11 and exhaust manifold 12, a carburetor 13 of any desired type being connected to the inlet manifold. The carburetor has an air inlet conduit 14 and a mixture discharge conduit 15, flow through the latter being controlled by means of the usual throttle valve 16. A throttle operating rod or wire 17 connected to an arm 18 which is rotatable with the throttle valve 16 serves to maintain the throttle valve in any desired position of adjustment.

If the air inlet conduit 14 of the carburetor is provided with a choke valve, I contemplate that such valve will either be removed or disconnected from any operating mechanism, as my invention makes manual operation of the choke valve unnecessary.

The device shown in the drawing embodies the invention in my prior Patent No. 1,577,765 in that I provide for the carburetor a branched air inlet-

passage, the two branches of which are formed in the body 20 of the attachment, which body is adapted to be secured as by means of set screws 21 over the air inlet opening of the conduit 14 of the carburetor. In the body 20, I provide two air passages 22 and 23 which receive air through separate openings but which meet and deliver air jointly to the inlet conduit 14 of the carburetor. Air flow through the two branch passages 22 and 23 is controlled respectively by valves 24 and 25. As in my prior Patent No. 1,577,765 one of the valves, here shown as the valve 24, is controlled by temperature-responsive mechanism; and the other valve, here shown as the valve 25, is controlled by means operated jointly with the starter 15 motor associated with the engine 10.

In this application, I contemplate that the position of the valve 24 will be determined in accordance with the temperature of the engine. To this end, the valve 24 is a butterfly valve mounted on a vertical shaft 26 which extends upward to a point adjacent the exhaust manifold 12 where it is connected to the inner end of a spirally coiled bi-metallic strip 27, the outer end of which is stationarily, although preferably adjustably, mounted. Desirably, the thermostat 27 is enclosed within a surrounding casing 28 one side of which is open and in proximity to the exhaust manifold 12. To provide for adjustment of the outer end of the thermostat 27, it may be secured as by a bolt 30 to a plate 31 on the outside of the casing 28. The bolt 30 passes through a slot in the wall of the casing 28 so that the bolt, the plate 31, and the outer end of the thermostat coil may be moved back and forth and clamped in any desired position of adjustment. The casing 28 which encloses the thermostat 27 may be connected to the body 20 through a tube 26' that encloses the shaft 26.

By reason of the construction just described, the position of the valve 24 will depend upon the temperature of the engine, since the thermostat 27 is mounted in close proximity to the exhaust manifold. When the engine is relatively cold, as it would be after remaining idle for a period of time, the valve 24 will be closed or nearly closed. When the engine begins to run, the temperature of the exhaust manifold 12 increases, and the thermostat 27 acts to move the valve 24 toward open position.

In order that the other valve 25 may be controlled jointly with the starter motor associated with the engine 10, I may make it in the form of a butterfly valve mounted on a shaft 35 which also carries an armature 36 disposed between the

pole pieces 37 of an electro-magnet 38, the supply of current to which is controlled by the starter switch. To this end, the electrical connections illustrated in Fig. 5 may be used. As shown in 5 that figure of the drawing, the starter motor 40 is connected in parallel with the electro-magnet 38, and the supply of current from the battery 41 to the starter 40 and electro-magnet 38 is controlled jointly by the starter switch 42.

10 When the electro-magnet 38 is de-energized, the valve 25 which controls the flow of air through the branch passage 23 desirably occupies a position dependent upon air temperature. To this end, I may associate with the shaft 35 a torsion spring 45 which tends to rotate the shaft 35 in a clockwise direction; and I may limit such rotation of the shaft by means of a thermostat 46. This thermostat is similar to the thermostat 27 in that it is formed of a spirally coiled bi-metallic 15 strip the inner end of which is secured to the shaft 35 and the outer end of which co-operates with an abutment 47 against which it is held by the action of the torsion spring 45. The thermostat 46 is arranged in such a manner that as the temperature to which it is responsive increases it collapses and permits the spring 45 to move the valve 25 toward open position.

The armature 36 is so constructed that when the electro-magnet 38 is energized the shaft 35 20 and the valve 25 will be rotated in a counter-clockwise direction against the force exerted by the spring 45 to close the valve 25. When the magnet 38 is de-energized, the spring 45 opens the valve 25, the extent of the opening depending 25 upon the condition of the thermostat 46.

Desirably, the abutment 47 which co-operates with the thermostat 46 to limit opening movement of the valve 25 is not a fixed abutment but is adjustable jointly with the throttle valve 16. 30 To this end, the abutment 47 may be in the form of a screw mounted in one arm of a bell crank 50 the other arm of which is connected to the throttle-operating arm 18 through a lost-motion connection 51. A torsion spring 52 associated 35 with the bell crank 50 tends to rotate such bell crank in a clockwise direction (Fig. 2), or in such a direction as to carry the abutment toward the free end of the thermostat 36. Movement of the bell crank 50 under the influence of the spring 52 40 is limited, as by arranging it so that it engages the tube 26'. The lost-motion connection 51 is arranged to provide for some opening movement of the throttle without movement of the bell crank 50. When the throttle is opened beyond a 45 predetermined point, however, the lost-motion provided by the connection 51 is taken up, the bell crank 50 is swung in a counter-clockwise direction, and the resultant movement of the abutment permits the valve 25 to open to a greater extent 50 than it otherwise could. Thus, when the abutment 51 is in engagement with the arm 50 it will cause corresponding movements of the throttle and choke-valve, the choke-valve being moved 55 toward open position as the throttle is moved toward open position, and vice versa.

Desirably, I provide in the circuit of the electro-magnet 38 a thermostatic switch 55 which is arranged to open to de-energize the magnet 38 if 60 the starter switch 42 be closed more than a predetermined length of time. The thermostatic switch 55 is conveniently formed of a piece of bi-metallic strip 56 which is covered with enamel or other suitable insulating material. About this 65 strip there is helically wound a ribbon 57 of ma-

terial having a relatively high electrical resistance.

The strip 56 and its associated ribbon 57 are conveniently mounted upon a bracket 58 having two ears 59 and 60. The ribbon 57 is insulated from one of these ears, and is connected to one end of the winding of the magnet 38. The other end of the ribbon 57 is normally in contact with the ear 60 to complete the connection of the electro-magnet to ground. As current flows through the resistance ribbon 57, it becomes heated, and the bi-metallic strip 56 bends upward to carry the end of the ribbon 57 out of engagement with the ear 60, thus opening the circuit of the electro-magnet 38.

In the drawing the valves 24 and 25 are illustrated in the positions they occupy when the engine is relatively cold. The valve 24 is near its closed position, while the valve 25 is partially open.

If, under such conditions, the starter switch 42 is closed, the starter 40 operates to crank the engine; and simultaneously therewith, the magnet 38 is energized to move the valve 25 toward closed position. This produces a choking effect which results in the production of an over-rich mixture in the carburetor, such an over-rich mixture being highly desirable in starting a cold engine. When the engine begins to run on its own power and the starter switch 42 is opened, the electro-magnet 38 is de-energized, and the spring 45 moves the valve 25 toward open position to increase the rate of air flow to the carburetor and to decrease the relative amount of fuel in the mixture which the carburetor delivers to the engine. The extent of this relative decrease in fuel proportion is dependent upon the condition of the thermostat 46, which in turn is dependent upon air temperature. On a cold day, for example, the opening of the valve 25 which follows the opening of the starter switch 42 will be less than on a hot day. This is desirable, as a relatively rich mixture is demanded when the engine is warming up in cold weather. As the engine continues to run its temperature increases to cause an increase in the temperature of the exhaust manifold 12. This latter increase in temperature causes the thermostat 27 to open the valve 24 thus further decreasing the richness of the mixture as the engine warms up.

When the engine reaches its normal operating 5 temperature, the valve 24 will be substantially fully open, so that the supply of air, and therefore the proportions of the mixture produced in the carburetor, will be controlled by the position of the valve 25. In cold weather, this valve will 5 be more nearly closed than it will in warm weather, thus automatically providing the slightly enriched mixture desirable for the best cold-weather operation.

Before the engine is thoroughly warm, the supply of air to the carburetor 13 is partially choked, and the rate at which the explosive mixture is supplied to the engine is therefore limited by the position of the valves 24 and 25 rather than by the position of the throttle valve. In such circumstances, the position occupied respectively by the valves 24 and 25 limit the maximum speed at which the engine can run. With my present invention, however, an extensive opening movement of the throttle valve causes 7 the lost-motion in the connection 51 to be taken up and the abutment 47 to be moved to permit an augmented opening of the valve 25. This increases both the supply of air to the carburetor and the quantity of explosive mixture which the 7

carburetor delivers to the engine and permits the engine to run at the desired high speed.

Under some circumstances the engine may fail to start for a reason independent of mixture conditions, and the operator may continue to hold the starter switch 42 closed. The continued cracking of the engine with both valves 24 and 25 closed would result in flooding the carburetor. This would produce no benefit and might subsequently be the cause of failure of the engine to start. It is for this reason that the thermostatic switch 55 is provided. As set forth above, this switch opens to de-energize the magnet 38 irrespective of the condition of the starter switch 42, after the magnet 38 has been energized for a predetermined length of time. I contemplate that this length of time will be insufficient to accomplish extensive flooding of the carburetor.

10 A device somewhat similar in purpose to the thermostatic switch 55 is shown in my Patent No. 1,913,131, which issued June 6, 1933. In that patent, however, the temperature responsive device is a variable resistance rather than a switch, 15 and effects gradual control of the choke valve. In addition, the electro-magnet device which moves the choke valve is in circuit with the ignition switch rather than with the starter switch as in this application. The claims of my prior 20 patent, however, are not all limited to these features.

I claim as my invention:

1. An attachment for the carburetor of an internal combustion engine, comprising a body 35 adapted to be mounted at the air inlet opening of the carburetor, said body being provided with two air passages both of which communicate with the carburetor air inlet opening when the attachment is in place, a valve in each of said 40 passages, a thermostat supported from said body in position to be responsive to engine temperature when the attachment is in place, said thermostat being operatively connected to one of said valves to control its position in accordance with engine temperature, the other of said 45 valves being biased toward open position, electro-magnetic means for moving said last named valve toward closed position, and a second thermostat for limiting opening movement of said 50 last named valve.

2. In combination with an internal combustion engine carburetor having a throttle valve, a choke valve for varying the quantity of air supplied to said carburetor, said choke valve being biased toward open position, a pair of co-operating abutments for limiting opening movement of said choke valve, and temperature responsive means for controlling the position of one of said abutments, the other of said abutments being operatively connected to said throttle valve through a lost-motion connection to increase the extent to which the choke valve opens as the throttle valve is opened.

3. In combination with the carburetor of an internal combustion engine, a rotatably mounted valve biased toward open position for controlling the supply of air to said carburetor, a thermostat rotatable with said valve, an abutment co-operating with said thermostat to limit opening movement of said valve, and electro-magnetic means for rotating said valve toward closed position and for moving said thermostat away from said abutment.

4. The invention set forth in claim 3 with the 75 addition that said carburetor is provided with a

throttle valve, said abutment being operatively connected to said throttle valve.

5. In combination with an internal combustion engine carburetor having a throttle valve, a choke valve for varying the quantity of air supplied to said carburetor, said choke valve being biased toward open position, a pair of co-operating abutments for limiting opening movement of said choke valve, and temperature responsive means for controlling the position of one of said abutments, the other of said abutments being operatively connected to said throttle valve.

6. In combination with an internal combustion engine carburetor having a throttle valve, a choke valve for varying the quantity of air supplied to said carburetor, said choke valve being biased toward open position, a pair of co-operating abutments for limiting opening movement of said choke valve, and temperature responsive means for controlling the position of one of said abutments, the other of said abutments being operatively connected to said throttle valve to increase the extent to which the choke valve opens as the throttle valve is opened.

7. In combination with an internal combustion engine carburetor having a throttle valve and a choke-valve, means for controlling the position of said choke-valve, said means including a device responsive to the temperature of the engine and operative to move said choke-valve toward 30 open position as the temperature of the engine rises, and mechanism operated with said throttle valve when said throttle valve is moving in a range of adjustment near its open position for moving said choke-valve toward open position as 35 the throttle valve approaches open position, said mechanism being inoperative to move said choke valve when said throttle valve is moving in another range of adjustment nearer its closed position.

40 8. In combination with an internal combustion engine carburetor having a throttle valve, a mixture enrichening device for said carburetor, a member, a temperature-responsive element operatively interconnecting said member and said mixture-enrichening device, a spring acting on said member and biasing said mixture-enrichening device to produce an enriched mixture, and a lost-motion connection between said throttle valve and said member for moving said member and temperature-responsive element to produce a mixture of decreased richness when said throttle valve approaches open position.

9. In combination with an internal combustion engine carburetor having a throttle valve, 55 a mixture enrichening device for said carburetor, a member, a temperature-responsive element operatively interconnecting said member and said mixture-enriching device, a spring acting on said member and biasing said mixture-enrichening device to produce an enriched mixture, and a lost-motion connection between said throttle valve and said member for moving said member and temperature-responsive element to produce a mixture of decreased richness when said throttle 60 valve approaches one of its limit positions.

10. In combination with an internal combustion engine having an electric starter motor, a carburetor for supplying explosive mixture to said engine, an electro-magnetic device for varying the proportions of the mixture produced in said carburetor, a switch for jointly controlling the supply of current to said device and said starter motor, and means operated by current supplied to said electro-magnetic device for cut- 70 75

ting off the supply of current thereto at a predetermined time after said switch is closed.

11. In combination with an internal combustion engine having an electric starter motor, a carburetor for supplying explosive mixture to said engine, an electro-magnetic device for varying the proportions of the mixture produced in said carburetor, a time-controlled switch in series with said electro-magnetic device, timing means 5 operable at a predetermined time after actuation to open said time-controlled switch, a source of current, and a control switch closable to simultaneously supply current to said starter motor and said electro-magnetic device and to actuate 10 said timing means.

12. In combination with an internal combustion engine having an electric starter motor, a carburetor for supplying explosive mixture to said engine, a device operative to increase the richness 20 of the mixture produced in said carburetor, timing mechanism operative at a predetermined time after actuation to render said device inoperative, and means for simultaneously actuating said timing mechanism and operating said device and 25 starter motor.

13. In a control mechanism for a carburetor having a choke-valve biased toward open position, a throttle, a thermostat tensioned to limit opening movement of said choke-valve and arranged 30 to ease its tension upon an increase in temperature, a spring also tensioned to produce closing movement of said choke valve, and means for relieving the tension of one of said tensioned 35 elements as the throttle moves into one of its limit positions.

14. In a control mechanism for a carburetor having a choke-valve biased toward open position, a throttle, a thermostat tensioned to limit opening movement of said choke-valve and arranged 40 to ease its tension upon an increase in temperature, a spring also tensioned to produce closing movement of said choke valve, and means for relieving the tension of one of said tensioned

elements as the throttle moves into open position.

15. In a control mechanism for a carburetor having a choke-valve biased toward open position, a throttle, a thermostat tensioned to limit opening movement of said choke-valve and arranged to ease its tension upon an increase in temperature, a spring also tensioned to produce closing movement of said choke valve, and means for relieving the tension of said thermostat as the 10 throttle moves into one of its limit positions.

16. In a control mechanism for a carburetor having a choke-valve biased toward open position, a throttle, a thermostat tensioned to limit opening movement of said choke-valve and arranged to ease its tension upon an increase in temperature, a spring also tensioned to produce closing movement of said choke valve, and means for relieving the tension of said thermostat as the 15 throttle moves into open position.

17. In combination with an internal combustion engine carburetor having a throttle valve, a choke-valve for said carburetor, a movable member, a temperature-responsive element operatively interconnecting said member and said 25 choke-valve, a spring biasing said member in a direction to close said choke-valve, and means for moving said member against said spring to produce an opening movement of said choke-valve when said throttle valve approaches one 30 of its limit positions.

18. In combination with an internal combustion engine carburetor having a throttle valve, a choke-valve for said carburetor, a movable member, a temperature-responsive element operatively interconnecting said member and said 35 choke-valve, a spring biasing said member in a direction to close said choke-valve, and means for moving said member against said spring to produce an opening movement of said choke-valve when said throttle valve approaches open 40 position.

GLEN R. SISSON.
